DOOR CLOSER

Harry L. Gordon, Derby, Conn.

Application August 20, 1954, Serial No. 451,160

6 Claims. (Cl. 16—76)

This invention relates to a means for closing doors and more particularly to a self-acting door closer.

In the door closer art there is known a spring hinge, that is, a device which is manufactured to combine both the operation of a hinge and spring means for closing a door. Such a device must be installed when the door is first hung, or if installation is desired after the door is hung, the door must be taken down, the old hinge removed and the new substituted therefor. As an improvement for such laborious installation, particularly where the door is already in place within its frame, it is obvious that it is desirable to provide means for closing the door which does not necessitate removal of the door from its hinges.

To accomplish this in the past, comparatively expensive devices in the nature of hydraulic door closers have been provided. Simple spring means for attachment to the door have also been provided. The drawback with such structures is that they require that something be attached to the door, often making for unsightliness. Where spring means have been used, additional installation also has been required in order that the spring be retained in operative position in relation to the door and its frame. But even where an additional fixture or bracket is attached for the purpose of holding the spring means in position, such bracket often fails in its contemplated operation, resulting in a failure of effective operation of the closer.

It is the primary object of this invention to provide a spring door closer which may be installed in any door which is already hung without removing the door from its mounting and which door closer will be securely held in operative position without the necessity of installation of any additional bracket or fixtures. The manner in which this is to be done is by making the door closer of such nature that it may be incorporated directly into the existing hinge on the door. Firm anchorage of the door closer is provided by the use of the hinge pin as the anchoring means. The manner of installation of the door closer is very simple. The hinge pin is removed from the door, passed through the door closer and reinserted into its position in which it engages the plates of the hinge. It is well known that the conventional hinge pin is formed with a portion to engage the hinge plates and with a head portion to hold the engaging portion in place. It is contemplated in this invention that the head portion be made to fulfill a double purpose, that is to hold the hinge plate engaging portion of the hinge pin in position, and also to anchor the door closer in operative position.

A further object of this invention is so to construct the door closer that the head portion of the hinge pin when the door closer is installed, will be completely out of sight within the door closer. It will be appreciated that such a construction will make for greater attractiveness of the unit after the door closer is installed. An object supplementing that just set forth is to provide a door closer which can accommodate within its interior the head

2

portion of any hinge pin regardless of shape. Such construction is indicated in recognition of the fact that the head portions of different hinge pins vary in size. Some may generally be designated acorn shaped, while the head portion of a modern hinge may well be in the form simply of a flat head.

It is still another object of this invention to provide means in the door closer structure whereby the spring pressure exerted by the door closer may be varied. This is to be done by increasing the initial torsional stress upon the spring and the door closer.

The final object of this invention is to provide a door closer which is simple in construction yet able effectively to carry out all of the foregoing objects. By prescribing simplicity, economy in fabrication will be assured.

How these and many other objects are to be implemented will be made clear from a consideration of the accompanying drawings wherein:

Fig. 1 shows an elevational view of a first embodiment of a door closer constructed according to this invention included as part of a conventional hinge;

Fig. 2 shows an enlarged view of the door closer and hinge pin head, as shown in Fig. 1, with a portion of the door closer broken away;

Fig. 3 shows a second embodiment of the present invention;

Fig. 4 is a top view of the second embodiment, and Fig. 5 is a section at 5—5 of Fig. 4.

In the drawings is shown a door 10 hung in a door frame 11, the hinging means being a hinge 12 of known construction. The hinge 12 has hinge plates 13 and 14 secured to the door frame and door respectively. Hinge pin 15 engages hinge plates 13 and 14. The hinge pin 15 consists of the hinge engaging portion 16 and a head portion 17 of larger diameter than the hinge engaging portion. The door closer 20 is included as a unit into the hinge. The door closer 20 consists of a helical torsion spring 21 having one turn 22 of smaller diameter than that of the balance of the spring. The diameter 40 of portion 22 of the door closer is smaller than the diameter of head portion 17 of the hinge pin, yet larger than hinge engaging portion 16 of the hinge pin. The balance of the helical spring 21 is of a diameter large enough to accommodate head portion 17 of hinge pin 15. Furthermore, the axial extent of helical spring 21 is greater than that of the corresponding dimension of head portion 17 of the hinge pin. Thus it will be appreciated that the hinge pin of a conventional door hinge may be removed, the hinge engaging portion passed through the helical spring 21 so that head portion 17 of the hinge pin 15 will be completely contained within the helical spring 21, and the bottom of head portion 17 will abut against turn 22 of the helical spring.

Extending in either direction from the helical spring are arms 23 and 24, arm 23 bearing against door frame 11 and arm 24 bearing against door 10. In operation it is obvious that the opening of door 10 will move arm 24 of the door closer backwardly to increase the torsional force exerted by helical spring 21 and transmitted through arm 24 to door 10 as a compressive force, so that when door 10 is opened the door closer will operate to urge it to resume its closed position.

In the second embodiment shown in Figs. 3, 4, and 5, the door closer, generally designated 20, includes a helical spring 21 having the arms 23 and 24, the spring being 65 contained within a tubular casing 27. The casing is closed at one end except for an aperture 28 in the bottom of said casing through which the hinge engaging portion 16 of hinge pin 15 may be inserted, but through which head portion 17 of hinge pin 15 will not pass. To assemble the spring 21 into the casing 27, arm 23 of the spring 21 is introduced into slot 31, and the spring is

than pressed into the casing until arm 23 reaches a position where it is free to move within the footed portion 32 of slot 31. Arm 23 thus extends from the assembly to contact door frame 11. Arm 24 of the spring 21 is then above the casing 27, thus extending from the spring 21 to contact the door panel 10. Thus, the arms 23 and 24 are free to operate in the same manner as heretofore described in connection with Figs. 1 and 2. When assembled as seen in the drawings, the closed end of the casing 27 is disposed about hinge engaging portion 16 immediately below head portion 17, such closed end being then positioned between the hinge 12, and the head portion 17 of the hinge pin 15.

Since some doors may be somewhat heavier than others, or where quicker closing may be desired, it is desirable to provide adjusting means for increasing the compressive force exerted by arm 24 against door 10 when the door is in any given position. This may be done simply by providing a threaded eye 25 near the extremity of arm 24 through which eye is threaded a stud 26, the disposition of the stud being substantially normal in relation to the door. Thus, when stud 26 is threaded inwardly toward the door while the door is closed the spacing between arm 24 and door 10 will be increased, and the torsional force exerted by helical spring 21 and transmitted through arm 24 will be increased while the door is in the closed position. Arm 23 may be similarly adjusted by a stud 26 threaded into an eye 25 at its extremity and contacting door frame 11.

While I have described two specific embodiments of my invention it is apparent that changes and modifications may be made therein without departing from the spirit of my invention.

I claim:

1. A door closer for use with a door hinge having a hinge pin with a hinge engaging portion and a head portion of larger diameter than said hinge engaging portion, comprising a helical spring having a pair of arms extending therefrom for engagement with a door and a door frame, said door being hung on said door frame by said hinge, the first of said arms being capable of exerting a compressive force against said door in its normal closed position, and the second capable of exerting a compressive force against the frame from which said door is hung, in such manner that when said door is opened the compressive force exerted by said first arm against said door is increased urging said door to resume its normal closed position, and a tubular casing axially enveloping said spring, said casing being closed at one end except for an aperture therein through which said hinge engaging portion of said hinge pin passes, but through which said head portion of said hinge pin cannot pass the closed end of said casing being disposed between said head portion of said hinge pin and said door hinge, whereby said door closer may be locked in operative position relative to said door and door frame, and slot means in said casing through which one of said arms extends, said slot means also permitting insertion of said spring into its operative relation with respect to said door and said frame within said casing.

60

2. The door closer claimed in claim 1 wherein the axial length of said casing is at least as great as the axial length of said spring.

3. The door closer claimed in claim 1 wherein the axial length of said casing is at least as great as the axial length of said spring, and the axial length of said spring is greater than that of the head portion of said hinge pin, whereby said head portion is completely surrounded axially by said casing.

4. In a door hinge including a hinge pin having a hinge engaging portion and a head portion of larger diameter than said hinge engaging portion, a door closer comprising a helical spring having a pair of arms extending therefrom for engagement with a door and a door frame, said door being hung on said door frame by said hinge, the first of said arms being capable of exerting a compressive force against said door in its normal closed position and the second capable of exerting a compressive force against the frame from which said door is hung, in such manner that when said door is opened the compressive force exerted by said first arm against said door is increased urging said door to resume its normal closed position, and a tubular casing axially enveloping said spring, said casing being closed at one end except for an aperture therein through which said hinge engaging portion of said hinge pin passes, but through which said head portion of said hinge pin cannot pass the closed end of said casing being disposed between said head portion of said hinge pin and said door hinge, the other end of said casing being open, whereby said door closer may be locked in operative position relative to said door and door frame, and slot means in said casing comprising an axial slot having a circumferentially extending footed portion through which one of said arms extends, said axial slot extending into the open end of said casing, whereby said spring may be inserted into its operative relation with respect to said door and frame within said casing.

5. The door closer claimed in claim 4 wherein the axial length of said casing is at least as great as the axial length of said spring and completely surrounds said head portion of said hinge pin.

10 15 20 25 30 35 40 45 50 55 60

6. The door closer claimed in claim 4 wherein the axial length of said casing is at least as great as the axial length of said spring, and the axial length of said spring is greater than that of the head portion of said hinge pin, whereby said head portion is completely surrounded axially by said casing.
